UNITED STATES PATENT OFFICE.

ALBERT HENDERSON, OF PITTSBURGH, PENNSYLVANIA, ASSIGNOR, BY MESNE ASSIGNMENTS, TO THE HENDERSON STRUCTURAL UNITS COMPANY, OF PITTSBURGH, PENNSYLVANIA, A CORPORATION OF DELAWARE.

CONCRETE BUILDING CONSTRUCTION.

Application filed October 20, 1923. Serial No. 669,695.

The present invention relates broadly to concrete building construction, and more particularly to the construction of concrete floors, girders and columns.

5 An object of the invention is to provide a novel floor construction consisting of pre-formed concrete blocks.

10 A further object of the invention is to provide a girder and floor construction in which 10 preformed concrete blocks are utilized both for the construction of the girder and of the floor.

15 Still another object of the invention is to provide a system of constructing columns, 15 girders and floors from preformed concrete blocks.

20 In the accompanying drawings, there is shown, for purposes of illustration only, one embodiment of my invention, it being understood 20 that the drawings do not define the limits of the invention, as changes may be made in the construction therein disclosed without departing from the spirit of the invention or scope of my broader claims.

25 In the drawings:

Figure 1 is a perspective view, partly in section, showing a column, a girder and a floor constructed from preformed concrete blocks;

30 Figure 2 is a detail view illustrating the method of tying the floor to the girder;

Figure 3 is a plan view corresponding to Figure 2; and

35 Figure 4 is a perspective view illustrating a preferred type of preformed concrete block used in the construction.

In Figure 4 there is illustrated a block of the general type disclosed in my prior Patent No. 1,446,796 of February 27, 1923. This 40 block is preferably formed of rectangular shape and of such dimensions that the block will have a weight which can be conveniently handled by a workman. A block in the form of a twelve inch cube is a convenient size 45 and will have a weight of approximately 125 pounds, more or less. The block 2 shown in Figure 4 is formed with a plurality of passages 3 extending longitudinally therethrough for receiving reinforcing tie rods 4 and is provided in its end faces with grooves 5 spaced from the sides of the block so as to leave a marginal seating face 6 at each end of the block. Other cross grooves 6 may be provided in the end faces of the block.

The groove 4 and the cross grooves 6 in each 55 end face leave projecting lugs 7 which will preferably have their outer surfaces flush with the marginal seating face 5. The longitudinally extending passages 3 open at their ends in the marginal grooves 4 and leave the 60 block with a solid central core.

In constructing a floor, a plurality of these 65 blocks may be arranged end to end in series and tied together by reinforcing tie rods 8 extending through the aligned passages 3 and embedded in grouting. The grouting 70 may be poured into the passages after the rods have been inserted through chipped out openings 9 formed in the meeting marginal faces 5 of certain of the blocks, such openings intersecting the grooves 4. The grouting not only fills the longitudinal passages 3, but also flows into and fills the grooves 4 and 6. When this grouting has set and hardened, the series of blocks will have become 75 united into a monolithic structure. A series of blocks so united constitutes a floor member 10. A plurality of such monolithic members may be formed on the ground and then hoisted into position by a crane or the 80 like and placed side by side to form a floor, as illustrated in Figure 1.

The floor constructed as described above 85 may be supported upon girders also constructed from blocks arranged in series. In the drawings, I have shown a girder 11 constructed of four courses of blocks so that the girder has a section composed of four blocks, but it will be obvious that the girder 90 may have a section composed of one block or any number of blocks, depending upon the load to be supported. Each course of the girder 11 consists of blocks arranged end to end in series and tied together by reinforcing rods 8 extending longitudinally therethrough, these rods being embedded in grouting, as in the floor construction. Where the section of the girder is composed 95 of a plurality of blocks, these blocks will preferably be tied together at the joints by reinforcing frames 12 positioned in the grooves 4, the end faces of the blocks being chipped out at 13 to accommodate such frames. When the grouting is poured 100 through chipped out openings 14 to fill the longitudinal passages 3, this grouting will flow into grooves 4 and cross grooves 6 in the end faces of the blocks and will embed 105

the reinforcing frames 12. When this grouting has set, the entire girder construction will be united into a monolithic structure.

In Figures 2 and 3 I have illustrated a convenient method of tying the floor structure to the girder structure. It will be noted that two series of aligned floor members are supported at one end upon the girder, so as to leave a space between the adjacent ends of the two series. Tie rods 8 of the two series project into this space and are connected together in the manner shown by bending the projecting ends of the rods so as to engage each other. Vertical tie rods 14 are positioned between the end faces of the blocks in the girder and have their lower ends bent at an angle and projected into certain of the longitudinal passages in the girder. These vertical tie rods have their upper ends bent at an angle and projected into certain of the longitudinal passages in the floor members 10. The space between adjacent ends of the two series of floor members is filled with grouting 15 which embeds the connected projecting ends of the tie rods 8 and also embeds the upper portions of the vertical tie rods 14, the lower portions of these tie rods being embedded in the grouting which fills the grooves in the meeting end faces of the blocks of the girder. It will be seen that this method of construction enables the floor to be effectively tied to the girder. In Figure 1 there is also shown a column 16 supporting the girder. This column may be built up of any desired number of vertical series of blocks, the blocks of each vertical series being tied together by tie rods 17 in the same manner as the blocks of the girder. Moreover, reinforcing frames 18 corresponding to the reinforcing frames 12 may be placed in the grooves in the end faces of the blocks at the joints of the column, in order to tie the series of blocks together. It will be seen by reference to Figure 1, that certain of the tie rods 17 of the column extend between the meeting end faces of certain of the blocks of the girder and also through the space between the two series of floor members. The advantages of the present invention will be manifest from the foregoing description. It will be seen that I have provided a system of construction whereby the main supporting elements in the interior of a building may be constructed substantially entirely out of blocks of the same form and dimensions, without the requirement of any field concrete work and the expensive forms which are necessary for such work. The blocks may be made of a weight convenient to be handled by a workman and supporting members of any desired strength may be provided by composing the section of such supporting members of any desired number of blocks. By the provision of a system of

this character enabling floors, girders and columns to be constructed from blocks of uniform size and dimensions, the problem of manufacture of the blocks at the central plant is greatly simplified, as is also the problem of construction. Moreover, my improved method of construction reduces to a minimum the amount of skilled labor required.

While my invention is particularly concerned with blocks formed of concrete, I do not wish to limit myself to the use of this material, as the blocks may be made out of other suitable materials if desired.

I claim:

1. In building construction, the combination of a girder and a floor supported thereby, said girder comprising blocks arranged end to end in series and tied together by reinforcing means extending longitudinally therethrough, and tie rods for tying floor members to said girder, each tie rod having its ends bent at an angle to the body thereof and extending into a passage of the girder and a floor member respectively, substantially as described.

2. In building construction, a girder, a plurality of floor members extending at right angles to said girder and resting at one end thereon, said girder comprising concrete blocks placed end to end in series and tied together by reinforcing means extending longitudinally therethrough, and said floor members being arranged side by side and each comprising concrete blocks placed end to end in series and tied together by reinforcing means extending longitudinally therethrough, and separate means for tying floor members to said girder, each of said means extending vertically between meeting end faces of certain of the blocks of said girder and interlocking with said girder and projecting above the same and interlocking with its floor member, substantially as described.

3. In building construction, a column, a girder supported by said column, and a floor supported by said girder, said column and said girder each comprising blocks arranged end to end in series and tied together by reinforcing means extending longitudinally therethrough, and said floor consisting of a plurality of members placed side by side and each consisting of blocks arranged end to end in series and tied together by reinforcing means extending longitudinally therethrough, and reinforcing means tying floor members to said girders, substantially as described.

4. In building construction, the combination of a girder and a floor supported thereby, said girder comprising blocks arranged end to end in series and tied together by reinforcing means extending longitudinally therethrough, and said floor being formed of

- a plurality of members placed side by side, each of said members consisting of blocks arranged end to end in series and tied together by reinforcing means extending longitudinally therethrough, and reinforcing means tying floor members to said girder, substantially all of the blocks in said girder and floor being of the same form and dimensions, substantially as described.
- 10 5. In building construction, a column, a girder supported by said column, and a floor supported by said girder, said column and said girder each comprising blocks arranged end to end in series and tied together by reinforcing means extending longitudinally therethrough, and said floor consisting of a plurality of members placed side by side and each consisting of blocks arranged end to end in series and tied together by reinforcing means extending longitudinally therethrough, and reinforcing means tying floor members to said girder, substantially all of the blocks in said column, girder and floor being of the same form and dimensions, substantially as described.
- 15 6. In building construction, the combination of a girder and a floor supported thereby, said floor being formed of two series of aligned members supported at one end upon the girder so as to leave a space between the adjacent ends of the two series, each of said members consisting of blocks arranged end to end in series and tied together by reinforcing rods extending longitudinally therethrough, the reinforcing rods of the two series projecting into said space between the adjacent ends of the two series and having the projecting ends of the rods of one series bent into interlocking engagement with the projecting ends of the rods of the other series, and grouting filling said space and embedding the connected ends of said rods, substantially as described.
- 20 7. In building construction, the combination of a girder and a floor supported thereby, said floor being formed of two series of aligned members supported at one end upon the girder so as to leave a space between the adjacent ends of the two series, each of said members consisting of blocks arranged end to end in series and tied together by reinforcing rods extending longitudinally therethrough, the reinforcing rods of the two series projecting into said space between the adjacent ends of the two series and having the projecting ends of the rods of one series bent into interlocking engagement with the projecting ends of the rods of the other series, and vertical tie rods positioned between the end faces of certain of the blocks of the girder and projecting into said space and tying the floor members to said girder, and grouting filling said space and embedding the connected ends of said reinforcing rods and said vertical tie rods, substantially as described.
- 25 8. In testimony whereof I have hereunto set my hand.

ALBERT HENDERSON.
